PARAFFIN CLEANER

Glenn R. Buckley and Walter A. McGrew,
Oklahoma City, Okla.

Application March 25, 1937, Serial No. 132,921

2 Claims. (Cl. 166—18)

This invention relates to certain improvements in devices for removing paraffin from the interior of oil well tubing, and the like.

Devices generally used for this purpose at present have one common difficulty. After they have been lowered into the well and the return movement has been started, and a considerable amount of paraffin accumulates above the scraper, a high degree of vacuum is created in the tubing below the scraper. This vacuum causes oil to be drawn into the lower end of the tubing and raised in the tubing some thirty-two or thirty-three feet. Further upward movement of the scraper tends to increase the vacuum, but the back pull of the oil in the tubing causes paraffin to force its way past the scraper in the tubing and return into the well.

It is the chief object of our invention, therefore, to provide a device of this class which embodies an air passage which affords communication between the space below the scraper and the space above the paraffin which is being carried upward by the scraper.

Another object is to provide a novel sealing arrangement which prevents the paraffin from passing the scraper as it is raised in the tubing.

Another object is to provide a device of this class embodying two or more scraper elements which serve to doubly seal the scraper against the sides of the tubing.

Other objects of the invention will be fully understood by a consideration of the following detailed description when read in connection with the accompanying drawing which form a part of this application. The drawing is to be considered illustrative and not restrictive.

In the drawing:

Figure 1 is a side elevation of the device in section, showing it in operative position within a well tubing;

Figure 2 is a sectional view of the upper end of the uppermost pipe section used in connection with our device, and shows the ports which afford communication with the space in the tubing below our cleaner;

Figure 3 is a top plan view of the sealing assembly shown in its relation to its supporting member, and to its positioning sleeve, the latter two elements being shown in section; and,

Figure 4 is a top plan view of the disc assembly, shown in relation to its supporting member, which latter is shown in section.

The invention comprises an upper disc supporting member 1 threaded exteriorly at its upper end, and threaded interiorly at its lower end, and

having a longitudinal passage 2 throughout its length. A second disc supporting member 3 is threaded at its upper end exteriorly for connection to the lower end of the member 1, and is also exteriorly threaded at its lower end, and 5 has a similar passage 4 throughout its length. Each of the members is provided with an annular shoulder intermediate its ends, and the shoulder of each member serves to support a disc assembly, designated as a whole by the numeral 10 5, and a sealing assembly, designated as a whole by the numeral 6.

At its lower end the supporting member 3 carries a valve cage 7, which has the usual annular conical valve seat 8 near its upper end, and 15 which houses a usual ball valve 9. The lower end of the valve cage is open with the exception of a pin 10, or like member, which serves to retain the ball in the cage.

Referring to Fig. 4, each disc assembly 5 includes a hinge member 11 to which are suitably hinged four sections 12, 13, 14 and 15, which together form a substantially disc-like scraper.

Referring to Fig. 3, each sealing assembly 6 comprises a central hinge member 16 to which 25 are hinged four flappers 17, 18, 19 and 20. Both the hinge members 11 and 16 are centrally bored to fit snugly on the reduced shanks of the members 1 and 3. The two assemblies 5 and 6 are held tightly on their respective shoulders and 30 against each other by similar sleeves 21 and 22, the lower ends of which seat on the hinge members 16, and the upper ends of which are contacted by the lower ends of the adjacent members 1, with the exception of the uppermost sleeve 35 22, the upper end of which is contacted by the lower end of a pipe section 23. The lower ends of each of said sleeves 21 and 22 are preferably provided with suitably spaced prongs 27, 28, 29 and 30 (Fig. 3) which are adapted to partially 40 encompass the central ring portions of the members 16, as shown.

We contemplate using a plurality of the pipe sections 23 above the scraper proper. If approximately one hundred feet of the tubing is to be 45 cleaned at one time then approximately one hundred feet of the pipe sections 23 will be used, and to the uppermost section 23 will be attached a pipe section 24 which is provided at its upper end with a plurality of ports, all of which are 50 designated by the numeral 25, and with threads for securing to the lower end of the usual operating rod 26.

In assembling the device the valve cage 7 is secured to the lower end of the member 3 and 55

the lower disc assembly 5 is slipped over the reduced upper shank of the member 3 and is allowed to drop on the intermediate shoulder. The sealing assembly 6 is then likewise placed on the reduced shank of the member 3 and is so positioned that its flappers 17, 18, 19 and 20 cover the spaces between the edges of the hinged sections 12, 13, 14 and 15 of the disc assembly, and lie flat against the upper surface of the adjacent edges of the sections 12, 13, 14 and 15. The sleeve 21 is then slipped over the reduced shank and a disc supporting member 1 is threadedly connected to the member 3, its lower end seating on the sleeve 21 which in turn forcibly holds the two assemblies 5 and 6 firmly in position. Another disc assembly and sealing assembly are then likewise positioned on the shoulder of the member 1, and a sleeve 22 is placed in position. If additional disc and sealing assemblies are desired, additional members 1 may be connected together, and the assemblies positioned as above described. The upper end of the uppermost member 1 is then threadedly connected to the pipe section 23, the lower end of which holds the uppermost sleeve 22 in position.

As many of the pipe sections 23 as desired are then connected together, with the pipe section 24 at the upper end of the uppermost section 23, and the operating rod 26 is then connected to the upper end of the section 24.

Operation

The device is now placed in the well tubing and lowered. As it is lowered the flappers 17, 18, 19 and 20, and the hinged sections 12, 13, 14 and 15 are free to pivot upward, which results in a reduction of the overall diameter of all the assemblies, thus permitting easy passage downward through the paraffin coated tubing. In case paraffin congests in the tubing below the scraper and enters the cage 1, the valve 9 is immediately forced to its seat and prevents the passage 4 from being obstructed by paraffin. After the device has been lowered a sufficient distance below the upper end of the paraffined section of the tubing, its movement is reversed. The hinged sections 12, 13, 14 and 15, and the sealing flappers 17, 18, 19 and 20 assume positions substantially at right angles to the wall of the tubing, the intermediate shoulders on the members 1 and 3 limiting their pivotal movement downward. As the scraper is drawn upward a considerable quantity of paraffin accumulates above the uppermost disc and sealing assemblies and is drawn upward with the scraper. The ball valve 9 remains open during the upward travel of the scraper, and since the passages 4 and 2 intercommunicate, and also communicate with the bore of the pipe section 23 and with the bore of the upper pipe section 24,

no vacuum can possibly be created in the tubing below the scraper, and thus there is no downward vacuum pull on the paraffin in the tubing above the scraper to cause the paraffin to pass the disc assemblies. Any paraffin which does pass the uppermost disc assembly will, of course, be lodged above the next lower assembly and will act as a double seal against the further downward passage of paraffin. This paraffin in between the scrapers will also aid considerably in guiding the entire device past the tubing joints which we have designated by the numeral 31.

Should there be a column of fluid above the tool in the well tubing such fluid would be free to enter the ports 25 and pass downward through the device into the casing below it.

While we have described and illustrated a specific embodiment of our invention we are aware that numerous alterations may be made therein, and we do not wish to be limited except by the prior art and by the scope of the appended claims.

We claim:

1. A device of the class described comprising a sectional elongated tube having a plurality of vertically spaced annular shoulders near its lower end, each shoulder adapted to support a scraper assembly; a removable scraper assembly securely held on each of said shoulders, and comprising a scraper disc assembly composed of a central hinge ring and four substantially quarter-circular scraper blades hinged thereto, and a disc sealing assembly composed of a central hinge ring and four flappers hinged thereto, said flappers adapted to seal the spaces between the edges of said scraper blades; and an upwardly closing normally open pressure closable valve carried on the lower end of said elongated tube and adapted to prevent the passage of fluid upward therethrough.

2. A scraper assembly for a paraffin scraper which includes a hollow central shank, said assembly comprising a scraper disc assembly including a central hinge ring adapted to be held in position by encircling the shank of the paraffin scraper, and four substantially quarter-circular scraper blades hinged to said ring; and also comprising a scraper disc sealing assembly which includes a central hinge ring likewise adapted to encircle the shank of the paraffin scraper, and four flappers hinged thereto, each flapper adapted to bridge and seal the space between two adjacent scraper blades of said first mentioned scraper disc assembly; and means for maintaining the relative radial positions of said scraper disc assembly and said scraper disc sealing assembly.
